UNITED STATES PATENT OFFICE.

STANLEY CORYTON HUGH ROBERTS, OF LONDON, ENGLAND.

SOUND-REPRODUCING MECHANISM.

Application filed April 24, 1922. Serial No. 556,221.

To all whom it may concern:

Be it known that I, STANLEY CORYTON HUGH ROBERTS, a subject of the King of Great Britain, and resident of London, England, have invented certain new and useful Improvements in or Relating to Sound-Reproducing Mechanisms, of which the following is a specification.

This invention relates to gramophones and has for its object to effect an improvement in the casing and structure of such instruments whereby a greater portability and a greater volume of sound are obtained than is usual with such instruments, and their cost of manufacture reduced.

The invention comprises a gramophone of the kind operatively mounted in a box, cabinet or casing wherein the amplifying horn is arranged within the hinged lid with its larger or outer end opening through the front or side of the lid, while its inner end is adapted to register with the outlet of the tone arm when the lid is closed.

The amplifying horn is of rectangular cross section, of wood, metal or other suitable material and two of its sides are preferably formed of, or arranged against, the material of one side and a portion of the top of the lid.

In the preferred construction of the casing the back member or wall of the box or casing to which the hinge of the lid is attached is deeper than the front member on which the front of the lid rests when closed, the engaging edges of the two sides of the box and lid being correspondingly inclined so that the front of the lid can be arranged to form the large end of the amplifying horn.

The box cabinet or casing may be provided with a horizontal partition preferably of light metal arranged beneath the record carrier or table and adapted to support the motor from its under side independently of the box, cabinet or casing, and provided with stops to support the lid in the closed position, and with legs or supports for holding it at the desired height in the box, cabinet or casing.

An embodiment of the invention is illustrated in the accompanying drawings, wherein:

Fig. 1 is a perspective view of the gramophone with the lid of the box or case open.

Fig. 2 is a perspective view of the casing closed, and

Fig. 3 is a sectional view of the end of the tone arm and its supporting bracket.

In these drawings the box is in the form of a case of which the lower portion 1 is deeper at the back than at the front. The lid 2 is hinged to the back wall of the case at 3 and is deeper at the front than at the back, the adjacent edges of the lid and cover at their sides being of such an inclination that when the lid is closed the top and bottom of the case will be parallel to one another.

The amplifying horn is of rectangular cross section and is built in the lid of the case, with the large open end of the horn extending over the whole of the front of the lid. A portion 8 of the top of the lid together with one side 9 of it form two of the sides of the horn, the other two sides being formed by the divisions or partitions 4 and 5, 4 being arranged diagonally in the lid of the case and in 5 the plane of the lower edges of the lid and provided at its rear portion with a hole 6 adapted—when the lid is closed—to register with the open end of the tone arm which is secured in the case on a bearing bracket 10. A flexible washer 30 is fixed around the top of the opening in the bracket 10 so that when the lid is closed it will form a sound proof joint between the rim 11 of the horn inlet 6 and the opening in the bracket 10 above the tone arm outlet.

The tone arm terminates in a vertical portion 14 adapted to form a vertical pivot provided with projecting portions or pins 15 fitting in an annular groove 16 in the bearing bracket 10 so as to form a vertical bearing or pivot about which the tone arm 13 can move horizontally. The bearing bracket 10 is formed on a partition 21 constructed of light metal and supports the tone arm the desired distance above the record 17 which is mounted on a table 18 driven by a motor 19 in the usual manner. The horizontal pivot about which the tone arm 13 can be lifted to raise the stylus from the record, in the example shown, consists of pins or tunnions 15 extending from the vertical portion 14 of the tone arm 13 into and adapted to be carried round in the groove 16 and so form also the vertical pivot of the tone arm.

The horizontal partition 21 on the under side of which the motor is secured is constructed of light metal and provided with enlarged openings shown in dotted lines, and

is provided with legs or supports 31, and stops 32 on which the lid 2 rests when closed. The spindle of the motor extends through one of the openings in the partition 21 so as 5 to support the record carrier or table 18 above it.

In order to protect the stylus and sound box from injury while the casing is being carried or handled, a hood 20 is provided on 10 the tone arm 13. This hook can be placed on a bracket 26 on the casing, when the tone arm is turned back when not required for use, and the bracket 26 is arranged at such a distance from the lid that the stylus and the sound 15 box will be held from engagement with any portion of the casing during carriage. The space below the framing partition 21 is designed as a store for records 22, and the front portion 23 of the case is hinged to the bottom 20 of the case and is of such a size that when folded against the front of the case it will cover the large open end of the amplifying horn, and is provided with any suitable fastening device 24 and a handle 25 25 whereby the case can be carried when the lid 2 is closed and the fastening device 24 secured.

The gramophone is started in the usual way after the front portion 23 has been lowered and the lid also lowered to bring the hole 6 of the amplifying horn in register with the upright outlet of the tone arm. When only a modified tone is required the lid is raised, and when it is desired to use 30 the amplifying horn when the lid of the case is open, the inlet of the amplifying horn and the outlet of the tone arm are connected by means of a flexible or telescopic pipe connection.

40 Also when the gramophone is operated with the lid 2 closed, any desired degree of modification of the sound reproduced can be obtained by varying the amount of opening

of the front 23 which may be provided with any suitable means for holding it at the angle required to give the desired extent of opening.

What I claim and desire to secure by Letters Patent is:—

1. A phonograph cabinet comprising a body and a cover hinged thereto, said cover being deeper at the front than at the back and open at the front, an amplifying horn in said cover, a record carrier rotatably mounted in said cabinet body, a tone arm, a standard at one back corner of the cabinet for supporting said tone arm so that it may connect with the inlet to the horn, one side of said horn being formed by one side of the cover near said inlet, while the opposite side of said horn extends diagonally across the cover to form a space therein in which the tone arm can move across the records above the level of the lower edge of the amplifier.

2. A phonograph cabinet comprising a body and a cover hinged thereto, said cover being deeper at the front than at the back and open at the front, an amplifying horn in said cover, a record carrier rotatably mounted in said cabinet body, a tone arm movable horizontally about a bearing, a standard at one back corner of the cabinet for supporting said tone arm so that it may connect with the inlet to the horn, the upper portion of said standard being formed as the bearing about which the tone arm can move horizontally across the record, and the cover being divided diagonally into two triangular portions one of which is occupied by the amplifying horn while the other forms a space in which the tone arm can move across the record above the level of the lower edge of the amplifier.

In witness whereof I affix my signature.

STANLEY CORYTON HUGH ROBERTS.
